UNITED STATES PATENT OFFICE.

PIERRE JOUANNEAUX, OF PARIS, FRANCE.

COMPRESSOR FOR FLUIDS.

Application filed February 25, 1924. Serial No. 695,062.

To all whom it may concern:

Be it known that I, PIERRE JOUANNEAUX, citizen of the Republic of France, residing at Paris, France, have invented certain new and useful Improvements in and Relating to Compressors for Fluids, of which the following is a specification.

This invention has for its object to provide an improved compressor of the cylinder and piston type for sucking, compressing and delivering fluids of all kinds.

A constructional form of an improved compressor according to this invention is illustrated by way of example in the accompanying drawings in which the single figure is a part-sectional elevation of the improved compressor.

The improved compressor comprises essentially a standard D capable of being fixed at any desired place. On the lower part or base plate of the standard there are provided two bearings in which is rotatably mounted an axle or pivot pin K on which is fixed the end of the rod O of a piston B. This piston is fitted with a leather valve I or other suitable valve adapted to seat itself upon a suction duct, and it is also formed with a delivery duct to which is fitted a pipe J of suitable shape and length.

The said piston is adapted to work in a cylinder A provided with cooling ribs A' and furnished at its upper end with an upstanding lug comprising near its free end a ball bearing h.

In this ball bearing there engages a crank-pin G fixed to a disk F rotated by a shaft E which revolves in bearings carried by the standard D and receives its motion through the medium of a pulley C from any suitable source of energy (not shown).

It will be perceived that when the shaft E is rotated, the crank-pin G will cause a vertical to-and-fro motion of the cylinder com-

bined with a simultaneous lateral oscillatory motion due to the axle pin K of the piston 45 rod O being mounted in the bearings on the base of the standard.

During its ascent the cylinder sucks fluid through the valve I, and in its descent the fluid is forced by it out through the delivering duct and the pipe J.

It is to be understood that the described constructional form of the improved compressor is given solely by way of example and that the improved compressor may be 55 constructionally modified in any way without thereby departing from the nature of the invention. For instance it may comprise a plurality of cylinders and pistons.

Having now particularly described and ascertained the nature of my said invention and in what manner the same is to be performed, I declare that what I claim is:—

A fluid compressor, comprising a standard provided with a base; a piston having 65 the lower end of its rod pivoted to said base, and having suction and delivery ducts for the fluid formed through its head, the suction duct being provided with a check valve; a cylinder wherein said piston works having 70 a closed upper end provided with a lug, and an open lower end; a drive shaft journaled in the upper end of the standard; a crank disk attached to said shaft and provided with a pin engaged with said lug, thereby to 75 positively impart to said cylinder, simultaneously, both an endwise reciprocatory movement and a lateral oscillatory movement; and a delivery pipe for the compressed fluid connected to the outer end of the delivery duct and extending through the open end of the cylinder.

In testimony whereof I affix my signature.

PIERRE JOUANNEAUX.
